UNITED STATES PATENT OFFICE.

ROBERT H. BENNETT, OF WASHINGTON, DISTRICT OF COLUMBIA.

COMBINED SWITCH AND FUSE BOX.

Application filed July 26, 1921. Serial No. 487,706.

To all whom it may concern:

Be it known that I, ROBERT H. BENNETT, a citizen of the United States, residing at Washington, in the District of Columbia, have invented certain new and useful improvements in Combined Switch and Fuse Boxes, of which the following is a specification.

This invention relates to switches and 10 more particularly to a combined multiple circuit switch and fuse box, particularly adapted for use in aircraft, automobile or motor boat constructions.

In the aircraft, automobile or motor boat industries it is common practice to provide 15 a single multi-way switch or a group of simple switches for the purpose of controlling the various lighting and miscellaneous electrical circuits inside of the machine. 20 The switch or switches are usually mounted upon the instrument board, and fuses for protecting these circuits are usually located behind the board or at some other desired point away from the switches. This practice 25 of locating the fuses away from the instrument board in a position not readily accessible to the operator may seriously inconvenience him when the renewal of fuses becomes necessary. This practice meets with 30 serious objections particularly when applied to aircraft, for obviously a pilot in flight cannot leave his position at the instrument board nor can the engineer or mechanic, not acting as pilot of large flying machines, 35 and dirigibles leave his position to renew a fuse located in any position, but one which is most readily accessible.

The combined switch and fuse box hereinafter described is particularly designed to 40 overcome this primary objection among others by providing a switch suitable in principle for controlling a plurality of circuits, each of which has associated therewith a fuse contained within and made part 45 of the switch, all of the fuses for the several circuits being easily exposed to view by the simple removal of the cover head of the switch.

In addition to providing a multi-way 50 switch combined with readily accessible fuses, the device hereinafter described overcomes other disadvantages of means for accomplishing similar results by taking a form which insures compactness and minimum 55 area for mounting where space on the in-

strument board is limited. A further object is the construction of a device of the above general character which will be light in weight, weather-proof in construction, and provided so far as possible with standard materials and fittings thereby reducing its cost of manufacture and assembly. The device further insures a positive electrical contact at each and every point of the switch and the principle of construction may be 60 readily adapted to any number of groupings on each electrical circuit as may be necessary, according to the use to which the device is put.

Other objects will be in part obvious and 70 in part hereinafter pointed out in connection with the accompanying sheets of drawings, showing one of various possible embodiments of the invention and in the several views of which corresponding reference 75 characters denote similar parts.

In these drawings,—

Figure 1 is a plan view of the complete device;

Figure 2 is an elevational view of the de- 80 vice as mounted upon the instrument board;

Figure 3 is a sectional view taken sub- 85 stantially on line 3—3 of Figure 4;

Figure 4 is a transverse horizontal sec- 90 tional view taken substantially through the niddle of Figure 1; and

Figure 5 is a diagrammatic view show- 95 ing the general plan of wiring.

The present invention will hereinafter be 100 described merely in general terms. The circuits as shown in Figure 1 indicate "off", "one", "two", "three", but obviously these legends may be changed to indicate "run- 105 ning or flight lights", "standing lights", "recognition lights", as used in aircraft. For automobiles, the terms "bright", "dim" and "parking" may be used.

Referring now particularly to Figure 4, 110 a dial plate 10 is adapted to be secured to the instrument board in any desired manner as by means of fastening screws 11. This dial plate is provided with an upstanding cylindrical sleeve portion 12 inclosing a cylindrical body member 13 of any suitable insulating material. This body portion is provided with a plurality of openings 14, these being shown in Figure 3, and a central opening 15, the openings 14 each being adapted to hold a fuse 16 as shown in Figure 4, which fuses are supported on springs 17

resting upon the heads 18 on binding posts or terminals 20. These springs insure positive contact through the fuses to the contact 21 which is connected by bridge piece 22 to a central or common terminal or contact 23. This common terminal is provided with a pin 24 adapted to have a locking engagement with spring arms 25 secured by means of a central contact or binding post 26. The 5 springs 17 also serve to initially eject the fuses into a position where they may be readily grasped for removal when such removal is desired. The contacts 21 and 23 are embedded in a suitable cover 27 of vulcanite or the like, which is provided with a plurality of spring arms 28 constituting an outer sleeve. The arms are slightly crimped as at 30 to form a means of holding this sleeve to the body sleeve 11, which is similarly given a crimped circle of slightly increased diameter as shown in Figure 4. Any other desired method of insuring a gripping connection or of holding the sleeves together, yet at the same time permitting the outer sleeve to rotate relatively to the other, 20 may be employed.

The cover 27 as shown in Figure 1, is preferably provided with a waved periphery whereby it may be easily grasped for turning or removing. An indicator such as an arrow 31 is preferably positioned in line with the two contacts 21 and 23 thereby to indicate to the pilot the position of the switches and to show which of the circuits 25 is in operation.

The operation and manner of using a device of this character is substantially as follows: Assume the parts to be assembled upon the instrument board, the pilot merely 40 grasps the cover 27 and turns the same relatively to the body portion of the fuse to complete any one of the plurality of the circuits as desired, the arrow pointing centrally to the legend, denoting the circuit. 45 If the light fails to operate, it may be presumed that the fuse for that particular circuit is blown, thereupon the operator removes the cover and all the several fuses are forced slightly outward by springs 17 so 50 that they may be conveniently grasped by the fingers and removed, and a substitute fuse placed in the vacant space without the necessity of the operator leaving his seat. The cover is then pressed back, the crimped arms 30 together with the central locking pin 24, securely holding the members in reassembled position.

In a switch construction of this character, 60 the operator can not only most conveniently remove the defective fuse, but the switch itself will indicate with the light circuit, the particular fuse which is defective so that the operator will know at once without testing all the fuses or examining them separately which one should be replaced.

It will thus be seen that the present invention embodies a simple, practical and inexpensive combined switch and fuse box particularly adapted for use on aircraft and automobiles where a plurality of circuits are used and where it is frequently necessary to replace a fuse most conveniently and with the least loss of time. 70

Without further analysis, the foregoing will so fully reveal the gist of this invention 75 that others can, by applying current knowledge, readily adapt it for various applications without omitting certain features that, from the standpoint of the prior art, fairly constitute essential characteristics of the 80 generic or specific aspects of this invention, and, therefore, such adaptations should and are intended to be comprehended within the meaning and range of equivalency of the 85 following claims.

I claim:

1. In a device of the character described, in combination, a switch body having a plurality of circuits, a removable fuse associated with each circuit, and rotatable means 90 for operating the desired circuit.

2. In a device of the character described, in combination, a switch body having a plurality of circuits, a removable fuse associated with each circuit, and means for operating the desired circuit, said means comprising a rotatable member carrying two terminals, one of which is common to all circuits, and the other selective to the desired circuit. 95

3. In a device of the character described, in combination, a switch body, a plurality of terminals associated therewith, an individually removable fuse for each terminal located within the switch body, and a rotatable switch member associated therewith adapted to successively co-act with the fuses. 105

4. In a device of the character described, in combination, a fuse body adapted to be secured to an instrument board, a plurality of binding posts associated therewith in connection with a plurality of circuits, one of said binding posts being common to all the circuits, a plurality of fuses, one for each circuit, located in the body portion of said device, and a member connected with said common terminal for completing the circuit through said terminal and the other circuits as desired. 110

5. In a device of the character described, in combination, a switch body having a plurality of terminals for connection with a plurality of circuits; a plurality of fuses, one associated with each terminal, a rotatable cover for said fuse body, and contacts carried by said cover adapted to co-act with said fuses. 120

6. In a device of the character described, in combination, a body member having a plurality of terminals for individual cir- 125 130

cuits, a fuse associated with each terminal in said body member, means permitting the removal of any of said fuses as desired, and means comprising a rotatable bridge for operating the desired circuit through its fuse to the exclusion of the others as desired.

7. In a device of the character described, in combination, a fuse body adapted to be secured to an instrument board, and provided with a plurality of cavities, a terminal associated with each of said cavities, one of said cavities being provided with a common terminal, each of the other of said cavities adapted to be fitted with a fuse, and a cover associated with said fuse body having a bridge piece for connecting the common terminal with the other terminals of independent circuits.

8. In a device of the character described, in combination, a fuse body adapted to be secured to an instrument board, and provided with a plurality of cavities, a terminal associated with each of said cavities, one of said cavities being provided with a common terminal, each of the other of said cavities adapted to be fitted with a fuse, and a cover associated with said fuse body having a bridge piece for connecting the common terminal with the other terminals associated with independent circuits, and means for securing said cover in position yet permitting relative rotary movement thereof.

9. In a device of the character described, in combination, a fuse body having a plurality of cavities, a terminal associated with each of said cavities, a bridge piece whereby one of said terminals may be made common to the others as desired, springs located in the bottom of the other of said cavities and resting upon the terminals, and fuses supported by said springs.

10. In a device of the character described, in combination, a fuse body having a plurality of cavities, a terminal associated with each of said cavities, a bridge whereby one of said terminals may be made common to any one of the others as desired, springs located in the bottom of the other of said cavities and resting upon the terminals, fuses supported by said springs, and a cover plate being a connection with the common terminal and one of said fuses as desired,

said springs being adapted to force out the fuses when said cover plate is removed.

11. In a device of the character described, in combination, a fuse body having a plurality of cavities, a terminal for a circuit associated with each of said cavities, one of said terminals being common to all other circuits, springs located in the bottom of the other said cavities and resting upon the terminals, fuses supported by said springs, a cover being a connection with the common terminal and one of said fuses as desired, said springs being adapted to force out the fuses when said cover is removed, and means for securing said cover in position, yet permitting relative rotary movement thereof.

12. In a device of the character described, in combination, a fuse body having a plurality of cavities, a terminal associated with each of said cavities, a plurality of independent circuits connected with said terminals, one of said terminals being common to all of said circuits, springs located in the bottom of the other of said cavities, removable fuses supported by said springs, and a cover plate having a bridge thereon acting as a connection with the common terminal and one of said fuses as desired.

13. In a device of the character described, in combination, an instrument board having an opening therein, a casing mounted in said opening, a plurality of terminals associated therewith, in connection with a plurality of circuits, springs in said casing associated with said terminals, fuses supported by said springs, and a cover plate on said casing, said springs adapted to eject said fuses when said cover plate is removed.

14. In a device of the character described, in combination, an instrument board having an opening therein, a casing mounted in said opening, a plurality of terminals associated therewith, in connection with a plurality of circuits, one of said terminals being common to all of said circuits, springs in said casing associated with said terminals, fuses supported by said springs, and a rotatable cover plate on said casing having a bridge acting as a connection with the common terminal and one of said fuses as desired.

In testimony whereof I affix my signature.
ROBERT H. BENNETT.
